(57) **CLAIM**

The ornamental design for an auto hood assembly, as shown and described.

DESCRIPTION

FIG. 1 is a front elevational view of an auto hood assembly showing our novel design;

FIG. 2 is a rear elevational view thereof;

FIG. 3 is a left side view thereof;

FIG. 4 is a right side view thereof;

FIG. 5 is a top plan view thereof; and,

FIG. 6 is a bottom plan view of an auto hood assembly of the present invention.
